SCAFFOLD.

Application filed May 17, 1927. Serial No. 192,097.

This invention relates to improvements in scaffolds of the class employed in the erection of buildings and the repairing, refacing, or painting or erected buildings.

One of the primary objects of the present invention is to provide a scaffold structure which may be readily erected and its component parts assembled and adjusted in accordance with the building structure which 10 is to be erected or upon which work is to be done.

Another object of the invention is to provide a scaffold structure embodying frame members of such construction that they may 15 be put to various uses and arranged in various ways in accordance with the character of the structure to be erected or the work to be done upon an erected structure.

Another object of the invention is to provide a novel means for connecting and relatively bracing the foot boards of a scaffold structure with respect to the uprights and with respect to one another and which means will likewise serve to maintain the uprights 25 in proper spaced upright parallel position, without the necessity of employing diagonal braces between adjacent uprights as is usually the custom.

Another object of the invention is to provide a novel arrangement whereby the scaffold structure may be erected so as to permit of one end of the foot boards extending beyond the scaffold structure proper, which is desirable under various conditions 35 encountered in the erection of buildings.

Another object of the invention is to provide novel means whereby the foot boards of scaffolds arranged at two adjacent sides of a building structure, being erected, may 40 be connected in overlapped relation at the corner of the structure, thus permitting the workmen to pass from one scaffold structure to the other without the necessity of descending to the ground surface.

Another object of the invention is to provide, in a scaffold structure, novel means for connecting the uprights of the structure, which means will facilitate assemblage and adjustment of the component parts of the structure so that it may be quickly set up 50 or taken down and extended either vertically or laterally as circumstances may require.

Another object of the invention is to pro-

vide novel means for anchoring the scaffold structure to the window frames of the building being erected or already erected, and which anchoring means will be positive in its engagement with the window frames and yet so constructed as to avoid any marring 55 or other damage to the frames.

Another object of the invention is to provide a scaffold structure which may be conveniently supported upon wheels so that it may be shifted from place to place or may 60 be erected in a substantially fixed position, either as desired and without any material alteration of the structure, in either event.

While the accompanying drawings and the description which is to follow, constitute 70 a disclosure of the preferred embodiment of the invention, it will be understood that various changes may be made within the scope or what is claimed.

In the accompanying drawings:

Fig. 1 is a view in front elevation of a scaffold constructed in accordance with the present invention, parts being broken away and parts being shown in section;

Fig. 2 is a side elevation of the scaffold, parts being shown in section;

Fig. 3 is a horizontal sectional view taken substantially on the line 3—3 of Figure 1 looking in the direction indicated by the arrows;

Fig. 4 is a detail vertical sectional view taken substantially on the line 4—4 of Figure 1 looking in the direction indicated by the arrows;

Fig. 5 is a similar view on the line 5—5 of Figure 1 looking in the direction indicated by the arrows;

Fig. 6 is a vertical longitudinal sectional view through a portion of the scaffold structure illustrating the bracing means provided 95 between the uprights and the foot boards;

Fig. 7 is a bottom plan view of a portion of the structure shown in Figure 6;

Fig. 8 is a vertical transverse sectional view taken substantially on the line 8—8 of Figure 6 looking in the direction indicated by the arrows;

Fig. 9 is a plan view of a portion of the scaffold structure illustrating the means provided for anchoring the structure with respect to the windows of the building to be erected or already erected;

Fig. 10 is a vertical transverse sectional

view taken substantially on the line 10—10 of Figure 9 looking in the direction indicated by the arrows;

Fig. 11 is a view partly in elevation and partly in section illustrating the means for anchoring the foot boards of the structure to the rungs of the uprights;

Fig. 12 is a plan view of a corner portion of the structure illustrating the manner in which the foot boards of two scaffold structures may be connected at the corner of a building;

Fig. 13 is a fragmentary front elevation of a modified form of scaffold structure;

Fig. 14 is a view partly in side elevation and partly in section illustrating parts of the structure assembled and adjusted to provide an upright ladder;

Fig. 15 is a side elevation of the structure shown in Figure 14;

Fig. 16 is a side elevation of a trestle or ladder structure built up by the use of parts of the scaffold structure embodying the invention;

Fig. 17 is a fragmentary view in front elevation of a modified form of one of the uprights for use as a ladder;

Fig. 18 is a similar view illustrating an arrangement of the parts whereby a ladder may be arranged in position supported partly by the floor or ground surface and partly by one of a flight of steps.

In the drawings the scaffold structure is illustrated as embodying a plurality of uprights 1 each of which comprises a pair of spaced upright parallel side members 2 and connecting rungs 3. The side members 2 of each upright will ordinarily be of wood and, in order to accommodate the rungs 3, the uprights will have their said side members formed with openings 4. Inasmuch as the invention contemplates the provision of any desired number of rungs, each side member 2 will be formed with a number of the openings 4 extending in a series longitudinally of the side member. Each of the rungs 3 preferably comprises a tubular body which is threaded at each end as indicated by the numeral 5, and clamping heads 6 are threaded onto each threaded end portion 3 as best shown in Figures 4 and 5 of the drawings and bear against the opposite faces of the upright side member 2 through which the threaded end of the rung 3 is fitted, where the rung is to extend merely between two of the uprights of a single one of the sections as shown for example more clearly in Figure 5 of the drawings. Each of the clamping heads 6 comprises a circular body having a threaded opening 7 located centrally thereof and formed upon one face with a short annular flange 8 which surrounds the said opening, the opposite faces of the bodies of the clamping members being preferably flat. It will be observed by reference to Figure 5 that in

anchoring or securing the ends of the rungs 3 in the side members 2 of the uprights 1, one of the clamping members 6 is threaded onto the end of the rung and this end of the rung is then fitted through the opening 4 whereupon the other clamping member is threaded onto the threaded end of the rung and tightened so as to bind the side member 2 between the two clamping members and thus securely anchor the parts in their connected relation.

Preferably lock nuts 9 are threaded onto the outer threaded ends of the rungs 3 and bear against the outer ends of the clamping members 6, each nut being formed in its engaging face with an annular recess 10 accommodating the end of the flange 8 upon the respective clamping member. It will be observed by reference to Figures 1 and 2 of the drawings, that, in the instance of some of the upright sections, the side members 2 thereof are spaced apart a greater distance than are the side members of the other sections of the uprights, this being most clearly shown in Fig. 2 of the drawings, and as a consequence the sections may be assembled end to end so that the upright may be made of any desired height.

In assembling the sections end to end, the ends of the narrower sections are arranged in overlapped relation within the ends of the wider sections, and the threaded outer ends of the rungs 3 which are engaged through the registering openings in the overlapped ends of the side bars of the connected sections, serve to connect the said side bars and prevent relative displacement thereof, the clamping members 6 being applied to and adjusted upon the threaded ends of the rungs 3 so as to engage the relatively remote sides of the overlapped ends of the side bars through which the ends of the rungs extend.

Preferably the side bars will be overlapped in such a manner that the overlapping ends of each two sections will be connected by two of the rungs, so that there can be no angular displacement of the connected sections of the uprights and the sections will therefore all occupy a common vertical plane. It will likewise be evident by reference to Figure 2 that the narrower and wider sections of each upright are alternately arranged, so that the assemblage of sections will be symmetrical throughout the entire height of the upright.

At this point it will be evident that any desired number of the upright sections may be connected together in the manner illustrated and described so that an upright of any height may be erected. It will be understood at this point that the rungs 3 serve not only to relatively brace and connect the side members 2 of the sections of the upright but they likewise serve as ladder rungs, so that a workman may ascend or descend from one line of foot boards to another.

The foot boards referred to above are indicated by the numeral 11 and may be of va-

rious lengths and of any desired width and, in order that the boards may be braced with respect to the uprights, the boards being disposed to rest upon corresponding rungs of adjacent uprights, means is provided which will now be described and which is most clearly illustrated in Figures 6, 7 and 8 of the drawings. The means referred to comprises a pair of clamps indicated in general by the numeral 12 and which clamps are secured to the foot boards 11 adjacent the overlapping ends of two associated boards. Each of the clamps comprises a plate 13 having threaded openings formed therein adjacent its ends, and a pair of clamping members 14 each comprising upper and lower spaced horizontally disposed portions 15 and 16 and a connecting intermediate portion 17. The upper portion 15 of each clamping member 14 is provided at its end and upon its under side with one or more downwardly projecting spurs 18 and the clamping members are assembled with the foot boards 11 by engagement with the opposite longitudinal edges of the boards, the spurs 18 biting into the upper side of the board engaged by the clamping members and the clamping members being in this manner securely anchored to the board against displacement. The plate 13 of each clamp is disposed against the under side of the respective foot board and the clamping members 14 are so assembled with the foot board 11 and the plate 13 that their lower portions 16 will extend beneath and in contact with the under sides of the plate 13 at the ends thereof these portions 16 being formed with longitudinally extending slots 19, and securing bolts 20 preferably provided with winged heads are fitted through the slots 19 and threaded into the openings in the ends of the plate 13 thus binding the portions 16 of the clamping members 14 to the said plate 13 and holding the clamping members against displacement with respect to the plate, the longitudinal edges of the foot board being of course received within the clamping members between the portions 15 and 16 thereof and abutting against the portions 17. The plate 13 of each clamp is provided upon its under side with a pair of spaced apertured ears 21, and brace arms 22, which are flattened at their upper ends, have their said upper ends engaged between the ears and connected thereto by transverse pivot pins 23. The brace arms 22 are inclined downwardly from the clamps upon the two boards which have their ends mutually overlapped, as most clearly shown in Figure 6 of the drawings, and the lower ends of the arms are threaded as indicated by the numeral 24 and are fitted into threaded sockets 25 which project radially at an angle with respect to each other from the upper side of a sleeve 26 which is slidably and yet snugly fitted upon the rung 3 which is next below the rung upon which

the overlapped ends of the foot boards 11 are supported as shown in the said Figure 6. It will now be evident that by the provision of this means, the foot boards are not only braced with respect to the uprights of the scaffold structure but are likewise braced with respect to each other so that there can be no relative displacement of the boards either with respect to each other or with respect to the uprights. Where the foot boards 11 overlap at their relatively adjacent ends as in Figure 6 and are supported at their said ends upon one of the rungs 3 of the upright, no connection is necessary between this rung and the overlapped ends of the boards, but where the boards extend over and are supported by other rungs of intermediate uprights, such a connection is provided and this connection is clearly shown in Figure 11 of the drawings and will now be described.

The means referred to above comprises a bar or plate 27 which is of a length slightly greater than the width of the foot board 11 and is disposed transversely of the upper side of the foot board to be anchored in position upon the rung 3 upon which it is supported. Bolts 28 are fitted through the ends of the bar 27 and extend downwardly from the said ends of the bar and through openings 29 formed in the rung 3, wing nuts 30 being threaded onto the projecting lower ends of the said bolts and being adapted to be tightened to bind against the under side of the rung so as to exert a downward pull upon the bar 27 and thus bind the foot board 11 against the upper side of the rung and secure the same against longitudinal displacement. It will be understood of course that this clamping action exerted by the bar 27 will likewise restrain the foot board against displacement longitudinally of the rung 3, and such displacement is positively prevented by reason of the presence of the bolts 28 at the opposite longitudinal edges of the foot board 11.

The means provided for anchoring the scaffold structure to and bracing the same with respect to the building wall, is best illustrated in Figures 3, 9 and 10 of the drawings and the said means includes rods 31 and 31', the rods being arranged end-to-end and having their meeting ends formed with screw threads 32 and being connected by a sleeve 32' which is interiorly threaded to receive the said ends of the rods. The rod 31 is fitted loosely through an opening formed in a head 33 which may be produced by twisting a length of bar metal at spaced points intermediate its ends to provide an intermediate portion through which the said rod 31 is engaged, and end portions 34 to which are pivotally connected arms 35. These arms constitute braces as will presently be explained and the arms are preferably formed from bar metal and each arm is twisted adjacent its end opposite its pivoted end as at 36 to provide a

portion 37 occupying a vertical plane at right angles to the plane occupied by the main portion of the arm. The portion 37 of each arm is bent to provide an outstanding laterally 5 projecting finger 38 and, in the assembled relation of the parts, the fingers 38 of the two arms 35 project in opposite directions and are engageable in the sash grooves of the window frame of the building indicated by the reference letter W, as most clearly shown in Figure 9 of the drawings. Links 39 are connected to the arms by pivot pins 40 engaged through the arms 35 and selectively through openings 39' in the links, and a pivot pin 42 is secured 10 through the inner ends of the links 39 and through the bifurcated outer end of the rod 31. As the rod 31 is loosely fitted through an opening in the intermediate portion of the head 33, it may have sliding movement 15 through said opening, and a nut 43 is threaded onto the threaded portion 32 of the rod 31 and is adjustable to bear against one side of the said intermediate portion of the head 33. A collar 44 is interiorly threaded and ad- 20 justably fitted onto the threaded portion 32 of the rod 31 and handle members 45 project radially in opposite directions from the said collar and may be grasped for the purpose of rotating the collar so as to feed the rod 31 25 through the opening in the head 33 in one direction or the other and thus effect adjustment of the links 39 to either spread the arms 35 and cause their fingers 38 to engage in the sash grooves of the window frame or to move 30 the arms toward each other to disengage the fingers from the said grooves. Clamping members 46 are employed in connection with the rod 31' and each of these members includes a vertically extending portion 47 having an opening therein through which the rod 35 is fitted, and a portion 48 which extends at right angles from the upper end of the portion 47, the portion 48 being designed to engage over the upper side of the edge portion 40 of the foot board 11 beneath which the rod 31' is disposed as shown in Figures 9 and 10 of the drawings, the portion 47 engaging against the opposite longitudinal edges of the board, a nut 49 being threaded onto the 45 threaded outer end of the rod 31' to be adjusted to bind one of the clamping members 46 and hold the other clamping member against the sleeve 32', and both members in engagement with the longitudinal edges of the foot board 11. It will now be understood 50 that by adjusting the collar 44, the arms 35 may be spread apart or moved toward each other and the bracing and anchoring device may therefore be readily adjusted and adapted to the window frame of the building with 55 respect to the wall of which the scaffold structure is to be supported, in spaced relation thereto. At this point it will be evident that due to the character of the means provided 60 for clamping the bracing devices to the foot

boards 11, the devices may be adjusted longitudinally of the boards in accordance with the spacing or location of the windows W. It will likewise be evident that the arms 35 of the devices may be angularly adjusted with 70 respect to each other so as to adapt the fingers 38 at the outer ends of the arms to engage the frames of windows of various widths. It will also be evident that the engagement of the fingers does not in any way mar or otherwise damage the window frames and yet the devices employed constitute a highly efficient means for relatively bracing the scaffold structure with respect to the building wall. 75

Any desired number of the uprights may be 80 employed, as will be understood from the foregoing description and from the illustrations, depending upon the length of the wall to be erected or worked upon, and as shown in Figures 1 and 3 of the drawings provision 85 may be made for the extension of the foot boards beyond the ends of the main scaffold structure. As previously stated, the side members 2 of the uprights may be made of varying length and these members are utilized 90 in various ways other than in the construction of the uprights as will now and also herein-after be made apparent. In Figures 1 and 3, there is illustrated an arrangement in which a 95 pair of the members 2, here indicated specifically by the numeral 50, are mounted at their lower ends upon the projecting threaded ends 5 of one of the rungs 3 and secured by one of the clamping members 6 and the nuts 9 associated therewith, the members 50 extending upwardly at an angle of inclination 100 from one end of the main scaffold structure and being bridged at their upper ends by another one of the rungs 3 which rung extends beneath the outer end of a foot board 11 which may be shorter than the foot boards employed in the main scaffold structure and which board at its other end is supported upon that one of the rungs 3 of the end section of the main scaffold structure which is 105 located in the same horizontal plane as the rung which supports the first mentioned end of the board. Braces 50', comprising a pair 110 of the members 2, are connected to and extend between the rungs 3 upon which the foot boards 11 are supported. If this end of the main scaffold structure is located at the corner of a building or if the scaffold structure is being employed within a building, in the latter instance in conjunction with another one of the scaffold structures arranged in spaced relation thereto, foot boards indicated specifically by the numeral 51 and corresponding in every way to the foot boards 11, may be supported at their ends upon the 115 foot boards 11 of the two scaffolds as shown in the said Figures 1 and 3. Thus, where the building is not of any considerable width, two of the scaffold structures may be arranged 120 at the opposite sides of the building and the 125 130

foot boards 51 may extend across the front or the rear of the building. It will also be evident that where the scaffold structure is employed within a building in finishing the 5 walls thereof, the extended structure illustrated and just described may project over shelving which has already been erected within the building, so that notwithstanding the presence of the shelving, workmen may reach 10 the wall of the building from the scaffold.

A somewhat similar arrangement of the foot boards is disclosed in Figures 1 and 12 of the drawings and in these figures the foot boards are illustrated as overlapping at their 15 ends in positions extending at right angles to each other, this arrangement being provided at the corner of a building. In order that the boards, which constitute members of two of the scaffold structures, may be connected in their overlapped relationship, clamping bars 52 corresponding in every way to the clamping bar 27, previously described, may be employed and arranged diagonally above and below the overlapped ends of the 20 foot boards as shown in the said Figs. 1 and 12, bolts 53, corresponding to the bolts 28, previously described, being fitted through the apertured ends of the bars and tightened to cause the bars to bind against the overlapped 25 ends of the foot boards and thus connect the same.

As the laws of many cities require that scaffold structures be provided with side rails to prevent the workmen falling therefrom, 30 the present invention contemplates the provision of such rails and in the most desirable manner, namely by utilization of members 54 which constitute the said rails and which are identical with the side members 2 35 of the uprights of the main scaffold structure, these members 54 being provided with openings 55 corresponding to the openings 4 in the members 2 and being mounted upon the rungs 3 as most clearly shown in Figures 40 1, 2 and 3 of the drawings, the members 54 being clamped by the clamping members 6 upon the respective rungs 3, against the side 45 members 2 between which they extend.

The lower ends of the uprights comprising the scaffold structure may be supported directly upon the ground or floor surface, or if preferred, means may be employed for supporting the structure so that it may be shifted from place to place, and where this is desirable, bearing sleeves 56 are fitted onto the projecting ends of the the lowermost rungs 3 of the uprights and abut at their inner ends against the flanges of the outer clamping members 6 and have fitted thereon the hubs 57 of wheels 58, the nuts 9 heretofore referred to being threaded onto the ends of the said rungs 3 and adjusted to bear against the outer ends of the bearing sleeves, the bearing sleeves being of a length greater than the length of 55 the hubs 57 of the wheels 58 so that the sleeves

will project at their outer ends beyond the outer ends of the hubs and be accommodated at their said ends in the grooves 10 formed in the respective nuts 9. This construction is most clearly shown in Figures 1, 2 and 4 of 70 the drawings.

As previously stated the rungs, foot boards, and side members of the uprights, are adapted to be arranged in various ways and put to various uses, and certain arrangements which 75 may be effected will now be described.

In the embodiment of the invention previously described and exemplified in Figure 1 of the drawings, the uprights and the foot boards are relatively braced by the structure 80 shown in Figures 6, 7 and 8 of the drawings, but, if desired, bracing members 59 corresponding in every respect to the members constituting the side members of the uprights, may be arranged in crossed relation as shown 85 in Figure 13 of the drawings and connected at their ends to the projecting ends of proper ones of the rungs 3 so as to relatively brace the uprights, the foot boards being held in place by the means shown in Figure 11 and 90 the structure, if desired, braced by the means shown in Figure 9, both as previously described. This constitutes a somewhat less expensive arrangement of parts and may be resorted to, although it is not as desirable as 95 the structure previously shown and described.

In Figures 14 and 15 of the drawings there is shown an upright ladder comprising upright side members 60 which are identical with the side members 2 of the uprights of 100 the main scaffold structure previously described and these uprights 60 may be of any desired length and of one piece or the upright as a whole may consist of several sections connected in the same manner as the sections of the previously described uprights. The spaced uprights 60 are connected by rungs 61 corresponding to the rungs 3 of the previously described embodiment, and the lower ends of the uprights 60 are preferably 105 designed to rest upon the ground or floor surface. Upwardly and inwardly inclined pairs of braces 62 which correspond in form to the side members 2 previously described are connected at their upper ends by means of one of the rungs 61 and the clamping members associated therewith, to the corresponding uprights 60, and these braces are relatively braced at their lower portions by a transverse or horizontal brace 63 which is connected near 110 its ends with rungs 61 which are arranged to extend between the braces 62 and, at their intermediate portions are connected to the ends of another one of the rungs 61 which extends between the lower portions of the uprights 60. This construction as thus far described may be employed alone, or, if desired, braces 64 corresponding to the bracing arms 22 previously described, may be employed at 115 the upper end of the structure to support a 120 125 130
